UNITED STATES PATENT OFFICE.

JAMES C. GILMER, OF CHICAGO, ILLINOIS.

FINISH MEANS FOR BUILDING MATERIALS.

Application filed March 14, 1924. Serial No. 699,192.

This invention relates to methods and means for producing an attractive and desirable finish on building materials and wall members such as bricks, blocks, tiles, panels and the like, and especially to a structural improvement for such materials, including finish bricks in particular.

Heretofore bricks and such devices have been faced with enamel formed directly upon and substantially integral with the body of the brick. This has been subject to certain limitations and defects, both in the process of manufacture and subsequent use and service under various conditions.

The main objects of this invention are to provide an improved construction and method of manufacture for bricks, blocks, tiles, panels and the like, where a durable high grade finish face is desired, as for instance enamel or japan; to provide for assembling and combining preformed finish plates with various forms of building blocks either preformed or formed with the plates attached thereto; to provide for separately finishing a face plate in any desired manner before attachment to or assemblage with the main body of the brick or other building member, of which it may usually well be substantially an integral part when finished; to provide building blocks, bricks, or the like, of very light material, comparable to wood or papier-mâché, and faced with complementary plates finished with enamel, japan, "bakelite", or the like; to provide bricks, etcetera, having complementary enameled or japanned finish plates of any suitable material, preferably fire-proof, adapted for interlocking attachment thereto, whereby the bricks proper and the finish plates may be made separately and subsequently assembled, either before or after the bricks have been set in a wall or other building structure; and to provide finish plates of improved structure, character and form for use as herein set forth, and adapted to withstand rough usage, weather, acids, fumes, etcetera.

An illustrative embodiment of this invention is shown by the accompanying drawings, in which—

Figure 1 is a perspective view of a brick which may be made of concrete or any composition desired and provided with an interchangeable face plate having a finished surface.

Fig. 2 is a longitudinal section at 2—2 on Fig. 3, through the brick of Fig. 1, illustrating how the face plate may be attached.

Fig. 3 is a transverse section at 3—3 on Fig. 2.

Fig. 4 shows a fragmentary corner detail of a form, partly in longitudinal section, in which the plate has resilient end lugs adapted to be sprung into apertures in the end of the brick in assembling the body and plate.

Fig. 5 shows a fragmentary corner of a brick having a permanently secured plate which may be attached to the brick in molding, and provided with an interchangeable face plate formed at its edges to interlock with the first mentioned plate.

Fig. 6 shows a corner of a brick provided with a permanently secured plate having a hollow lug of special form, and a finish plate detachably secured by means of a resilient arm projecting into said lug for interlocking therewith.

In the structural embodiment shown in Fig. 1, the building block is in the form of a brick comprising a body part 1 and a face plate 2. Depressions 3 molded in the sides of the body 1 lessen the weight of the brick and provide a better hold for the mortar when the brick is laid in a wall. This form of brick may have a section such as shown in Fig. 2 or as in Fig. 7. The body 1 may be composed of ordinary brick-clay, concrete, wood-fiber, sawdust-compound or any other suitable material, and the plate 2 may consist of metal, fiber-board or other composition having a finish surface and may well include a layer of japan, enamel or other material adapted for the purpose and preferably capable of manufacture in various colors as may be required.

Figs. 2 to 5 and 7 illustrate different forms of finish plates adapted to be molded of cast metal, as for instance iron. In the embodiment of Fig. 1 the brick body 4 is formed with apertures 5 adapted to receive the resilient lugs 6 of the face plate 7, each of said lugs having a shoulder or catch part 8 to engage a corresponding shoulder 9 on the brick body.

Referring to Fig. 4, the interchangeable plate 26 is provided with a resilient end lug 27 having an inwardly turned tip 28 adapted to fit in the aperture 29 of the body 30.

The embodiment shown in Fig. 5 includes a body part 31 having a foundation plate 32 permanently secured thereto by means of a lug 33 integral with said plate and struck up therefrom, in combination with a face plate 34 formed with inwardly turned edges 35 to embrace the overhanging inclined edges 36 of said base plate. Said inwardly turned edges preferably extend only on two opposite sides so that the finish plate may be applied by endwise movement relative to the plate 32.

In Fig. 6 is shown a molded body member 37 having a foundation plate 38 permanently secured thereto by means of hollow lugs 39 set in said body. A finish plate 40 is demountably secured to said foundation plate by means of resilient lugs 41, formed to yieldingly engage lugs 39 which lugs 39 and 41 are formed to interlock as at 42.

It is apparent that any desired coloring effect may be carried out, and that various designs may be effected consistent with the shape and size of the blocks used, the face plates being variously colored in accordance with the requirements in any particular instance. It will be apparent in view of Fig. 6 that the ornamental design may be changed whenever desired by removing the resiliently held face plates 40, or part of them, and rearranging same or substituting plates of different colors.

One of the main artistic advantages of using finish plates such as I describe arises from the enamel and the metal, for instance iron, having substantially the same coefficient of expansion, by reason of which cracking, checking and chipping off of the finish is avoided. This is a serious difficulty with ordinary enamel faced tiles and bricks when exposed to the weather or to wide fluctuations of temperature.

For interior use, as in partitions either permanent or temporary, light weight blocks may well be used. By judicious selection of colors very pleasing decorative de-

signs may be accomplished for the home, as well as for the office.

The sanitary character of such bricks render them especially desirable for finishing interiors for restaurants, dining rooms, bathrooms and such places.

Although several embodiments of this invention are herein shown and described it is to be understood that no attempt has been made to show all practical embodiments of the invention, and it will be understood that some of the details shown and described may be altered or omitted without departing from the spirit of this invention as defined by the following claims.

I claim:

1. A wall member comprising a body part and a mechanically retained structurally distinct complementary face plate of metal having a finish surface of enamel thereon.

2. A wall member comprising a body part and a metallic face plate having a non-corroding finish surface thereon, said plate having resilient fastening means and being at all times interchangeable relative to said body part.

3. A wall having a decorative color design on its face, said wall comprising a plurality of blocks each having a structurally distinct complementary face plate characterized by specific coloring and having mechanical means for attaching the same after the main body of the block is set in place as in a wall.

4. A wall having a decorative design on its face, said wall comprising a plurality of blocks each having an interchangeable face plate characterized by a specific color, the several blocks and plates having interfitting mutually releasable connective means, and the wall design being variable by substituting different face plates having appropriate colors for the several blocks.

Signed at Chicago this 12th day of March, 1924.

JAMES C. GILMER.
